United States Patent Office

Des. 228,619
Patented Oct. 16, 1973

228,619

LOCK

Sidney Falk and Patrick M. Trainor, Chicago, Ill.,
assignors to Fort Lock Corporation, Chicago, Ill.

Filed Feb. 25, 1972, Ser. No. 229,621

Term of patent 14 years

Int. Cl. D8—07
U.S. Cl. D8—113

FIG. 1 is a perspective view of the lock with the center portion omitted for convenience of illustration as indicated by the broken lines;

FIG. 2 is a fragmentary perspective view showing the lock in an opened position;

FIG. 3 is a fragmentary plan view showing the lock body and associated structural detail;

FIG. 4 is a fragmentary plan view showing the lock in the closed position;

FIG. 5 is a side view of the lock body showing a key entryway; and

FIG. 6 is a view taken substantially in the plane of the line 6—6 in FIG. 1 and showing the top of the lock body.

We claim:

The ornamental design for a lock, as shown.
